 Chicago Pneumatic Tool Company, New York,
 N. Y., a corporation of New Jersey

Application May 30, 1944, Serial No. 538,008

15 Claims. (Cl. 218—19)

This invention relates to power tools for pulling a mandrel or draw pin while applying the reaction to a tubular element surrounding the mandrel, and more particularly to a portable pneumatic gun for installing blind rivets in sheet metal structures.

An object of the invention is the provision of a riveting machine of the indicated character which is capable, after setting the tubular element or rivet shell, of modifying the operation and forcing an initially integral collar upon the rivet shell down into the latter within the head thereof in order to lock said shell permanently upon the mandrel, and finally breaking off the mandrel above the upset shell.

Another object is to have such a riveting machine which is sufficiently compact to be conveniently held in the hand and applied to the work at will, while the machine or tool as a whole has such a well designed form that it at all times provides a satisfactory visibility of the work and of the rivets being set.

A further object is to set a blind rivet by power means which include a wedge and roller arrangement for multiplying the pressure derived from a reciprocating piston. According to a feature of this invention the upper roller is connected to the mandrel to pull the latter while the lower rollers are mounted on a track which applies the reaction to a primary anvil to set the rivet shell.

A still further object is to shift the point of reaction automatically from the primary anvil to a secondary anvil which is positioned to force the locking collar between the rivet pin and shell. Accordingly, another feature of the invention resides in an arrangement for frictionally holding the track in engagement with the primary anvil until a predetermined wedging, or setting, pressure has been attained, then releasing the pressure to permit the track to be shifted and then applying the reaction to the secondary or locking anvil.

Other objects and the advantages of the invention will appear more fully in detail in the following specification in connection with the accompanying drawings, in which:

Fig. 1 is a side elevation of the riveting machine embodying the present invention, illustrating the same as held in the hand of an operator in active use;

Fig. 2 is a top plan view, partly in section of the apparatus of Fig. 1 on a larger scale;

Fig. 3 is a transverse section of the tool looking forward as indicated by the arrows 3 in Fig. 5;

Fig. 4 is another section of the tool on line 4—4 in Fig. 5 looking rearward;

Fig. 5 is a longitudinal section of the entire apparatus, showing a mandrel inserted into a hollow rivet element and gripped in the forward chuck portion of the tool and the parts of the latter generally disposed in initial position ready for operation;

Fig. 6 is a front view in elevation of the pulling spindle which actuates the mandrel aforesaid;

Fig. 7 is a cross section of the tool as indicated by the arrows 7 in Fig. 5;

Fig. 8 is a detail view in section of one of the spring supporting washers;

Fig. 9 is a detail view of one of the spacer rivets that hold the side arms in spaced parallel relation;

Fig. 10 is a detail view of the transverse shaft mounted between the side arms and within the roller;

Fig. 11 is a longitudinal section generally similar to Fig. 5 but shows the parts of the tool operated to set the rivet;

Fig. 12 is a detail view of the sleeve which carries the outer anvil;

Figs. 13 and 14 are plan and side views respectively of the bushing which carries the inner anvil;

Figs. 15, 16 and 17 are plan, side and rear views respectively of the stationary bearing member which receives the thrust of the track or channel bar;

Fig. 18 is a detail view of the ratchet or retainer for the mandrel;

Fig. 19 is a longitudinal section similar to Figs. 5 and 11 illustrating the operation of driving a locking collar and breaking off the mandrel;

Fig. 20 is a sub-assembly view in side elevation, showing a side arm, spring supporting washer, and spring connected together;

Fig. 21 is a transverse section taken on line 21—21 in Fig. 5;

Fig. 22 is an enlarged scale section of a pair of metal or other work sheets showing rivets and associated mandrels in three stages of operation; and

Fig. 23 is an enlarged longitudinal section through the cylinder casing.

In several types of metal structures at least partly consist of sheet metal or metal of light section, and particularly in the fuselage structure of aircraft, the metal sheets forming the skin of the latter have some areas which are not conveniently accessible from other than the out-

side, necessitating the use of special hollow rivets, termed "blind rivets" introduced and set exclusively from the outside. The present riveting machine or tool of the invention is particularly designed to set and permanently lock such blind rivets securely in place in convenient and speedy manner.

The device is of the type operated by an elastic fluid such as compressed air and is thus preferably a pneumatic riveting machine equipped to set a blind rivet in several steps which automatically follow each other in quick succession, that is by first setting the rivet by pulling upon the mandrel which extends through the tubular element or shell of the rivet, breaking off and wedging a collar down into the rivet head about the mandrel and finally breaking off the latter above the rivet head, all without special attention on the part of the operator.

Hence referring again to the drawings, in the practice of the invention an apparatus embodying the latter is disclosed as exteriorly comprising a cylinder casing 10 forming the rear body portion thereof, with an adapter 11 secured thereto by screws 12 and connecting the casing with an intermediate elongated and relatively narrow, hollow grip member 13 adapted to be held in the hand as shown in Fig. 1. The intermediate elongated grip member is secured to the adapter by upper bolts or rivets 14 (one shown) and by lower rivets 15 which simultaneously hold the rear supporting block 16 in place within flange 17 of the adapter, the purpose of which block will presently be explained. At the front end of the grip member a tubular spindle casing 18 is welded, brazed or otherwise secured thereto, the grip member 13 being readily made of sheet metal bent into shape or shaped from tubing and the spindle casing 18 from a metal tube, while casing 10 and adapter 11 are preferably made of cast metal such as magnesium alloy. On the upper portion of the intermediate grip member is fixed a hand stop 19 and beneath said member is secured a bracket 21 bent down at the rear to form a finger stop 22 and at the other end bent down forwardly to serve as a support or bearing 23 for the pivot pin 24 of a rearwardly directed throttle trigger 25. The hand stop 19 and bracket 21 may be secured to grip member 13 by brazing or welding.

The stops 19 and 22 are designed to properly locate the operator's hand 26 (Fig. 1) in position upon the grip member to allow the index finger 27 to engage the trigger conveniently for operation. As the trigger pivots about pivot pin 24, it is capable of longitudinally shifting a trigger rod 28 connected to said trigger by a trigger pin 29, occupying a bottom slot 31 and slidably supported on bracket 21 and flange 17, while terminating at the rear in a hook 32 overhanging the rockable throttle cross arm 33 located within the adapter and arranged to fulcrum on the pin 34 fixed in the latter and engaging the cross arm intermediate the ends thereof. At its outer end the cross arm has a recessed portion 35 facing the rear and receiving one end of throttle push pin 36 which at its other end directly abuts the front end of the spindle or body portion 37 of the throttle valve 38, the spindle being movably guided in valve bushing 39 fixed in bore 40 in casing 10 and provided with a valve seat 41 against which valve 38 is urged by valve spring 42. The latter extends into fixture 43 screwed into the rear of casing 10 and forming the motive fluid inlet port to which an air hose 44 connected to a source of fluid

supply may be attached. The throttle valve spindle 37 has a neck 45 connecting the same with the valve head 38 proper. Manually depressing the trigger 25 toward bracket 21 causes the trigger to draw rod 28 forward and rock the cross arm upon fulcrum pin 34 from the position of Fig. 5 to that of Fig. 11, while push pin 36 and valve spindle 37 are both pushed rearward to shift valve head 38 off its seat 41 in opposition to spring 42, which allows pressure fluid from inlet aperture 46 in fixture 43 to pass the valve seat and proceed about the neck 45 and thereafter travel up through a passage 47 opening into the throttle valve bushing 39. Passage 47 communicates above the piston chamber 48 with valve chamber 49 of a slide shift valve 50 through intercommunicating ports 51. The valve is provided with a pair of valve heads 52, 53 spaced apart and slidably mounted in two aligned valve bushings 54, 55 fixed in the cylinder casing with a gap 56 between them in a manner and for a reason which will presently appear.

The piston chamber 48 contains a relatively thin piston head 57 substantially consisting of a plate having a cup leather 58 to provide a tight sliding fit in said chamber, said leather being held in assembled relation with the piston by a retaining plate 59 secured to the rear of the piston by the nut 60 screwed upon the rear end of the piston rod 61, the nut also serving to fix the piston rod to the front of the piston head, so that the piston rod will be positively moved longitudinally by the piston head. The piston chamber 48 is provided rearwardly with a projection 62 serving as a stop to limit rearward movement of the piston and insure that a predetermined space will be presented behind said piston for introduction of pressure fluid to operate the latter. When the trigger is operated to introduce pressure fluid into shift valve chamber 49 through passage 47 as already outlined, valve 50 first occupying the extreme rear position of Figs. 5 and 23, the fluid immediately passes from valve chamber 49 down through gap 56 into piston chamber 48 rearwardly of piston 57 and drives the latter and piston rod 61 forward for initially setting a rivet generally indicated at 63, which is thereafter further set and finally finished and parted from the device, as will be described in detail.

Leaving the piston and valve control therefor for the time being, attention is directed to the forward end of the piston rod and the apparatus as a whole. The piston rod has a self-adjusting or self-aligning connection 64 with an operating wedge 65 mounted to ride upon a series of roller bearings 66 retained in operative association by a roller bearing cage 67 and rolling upon a lower channel-shaped arm or track member 68. The bearing cage terminates rearwardly in a pair of hooks 69 (one shown) projecting upwardly between studs 71 extending to both sides of piston rod 61 and the side studs 72 extending inwardly from the side walls of the channel-shaped track member in order to insure that the cage with its roller bearings will constantly follow the movements of the wedge and maintain the roller bearings in proper position beneath the same. The rear end of the track member rests slidably on the previously mentioned support block 16 and is provided with a reduced or limited fulcrum edge 73 to allow rocking thereon involving a slight raising and lowering of the forward end 74 of said member 75 in a manner peculiar to the invention.

At the sides of the wedge are located a pair of side arms 75 (Fig. 7) secured together in mutually spaced relation by a plurality of spacer rivets 76 (Fig. 9), and intermediate the ends, said arms are provided with a transverse shaft 77 (Fig. 10) forming an inner race for a group of roller bearings 78 upon which a roller 79 is rotatably mounted in a position adapting this roller to be engaged by the wedge 65 and raised thereby when the wedge travels in the forward direction. Rearwardly the side arms are pivoted on two bushings 81 which are supported on transverse bearing shaft 82 fixed in the adapter 11, with the ends extending through the sides of the latter and exteriorly thereof having resilient retaining rings 83 seated in grooves 84 (Fig. 21) retaining the shaft in position in order for said shaft to form a very stable fulcrum and point of reaction for certain of the interior operating parts of the apparatus, and to be accessible from the outside to facilitate assembling and disassembling the apparatus. Within the spindle casing 18 the front ends 85 (one shown) of the side arms engage in the side recesses 86 (Fig. 6) in the head 87 of a pulling spindle 88 whose upper end terminates in a reduced tubular portion 89. To the latter is connected the lower end of a coiled metal strip or volute spring 91 secured within the upper end of the spindle casing by a retaining ring 92 and serving as an ejector chute for broken rivet mandrels cast off during operation. The spindle is hollow throughout and extends downwardly to form a continuation of the ejector chute, having a lower threaded hub 93 and terminating below the latter in a reduced hollow end portion 94, a chuck 95 being screwed upon hub 93 against spindle shoulder 96 above the thread and provided with the chuck jaws 97 co-operating with the conventional inner tapering chuck walls 98 thereof to grip the upper serrated end of a rivet mandrel or pin 101. The latter is brought into position by inserting said serrated end first through fixed outer anvil 102 screwed into the rigid lower end 103 of the stationary outer anvil sleeve or thrust bushing 104 (Fig. 12) fitted into the spindle casing 18 with the lower end of the latter abutting the flange 105 of sleeve 104, while a further flange 106 on said anvil sleeve, located in a recess 107 in the spindle casing serves to retain said sleeve in place. The upper portion of sleeve 104 is slotted to enable the flanged or beaded end 106 to enter the spindle casing 18 during assembly and to spring outward when it attains its operative position.

Within the outer anvil is fitted an inner anvil 108 through which the mandrel is passed and thereafter the latter is inserted through inner anvil thrust washer 109 and through the mandrel ratchet or retainer 111 (Fig. 18) immediately above the washer which is adapted to engage with the serrations 112 of the mandrel to prevent accidental return or loss of the inserted mandrel. The inner anvil is substantially a slidably mounted tube reinforced at the upper end by a flange 113 for withstanding the pressure of the thrust washer during operation when depressed by the slidable short thrust bushing 114 above said washer, the latter bushing being surmounted and operated by the main inner anvil sleeve or thrust bushing 115. The anvil 108 and the bushings 114 and 115 combine to form a spindle member slidably mounted within the spindle casing 18, 104 and operated independently of the chuck into the jaws 97 of which the mandrel is inserted. The mentioned jaws of the chuck have

their inner gripping sides 116 toothed to fit the serrations 112 of the mandrel (Fig. 22) in order to prevent slipping of the mandrel out of the chuck. Moreover, within said chuck is a follower ring 117 pressing on the jaws 97 under the bias of the follower spring 118 surrounding the lower reduced end portion 94 of the spindle, allowing the end of the mandrel to be thrust upwardly between the jaws which spread open to accommodate the same, until the final position of the mandrel is reached, when the spring urging the ring downward will thereby tend to close the jaws upon said mandrel. The mandrel proper fits slidably into the inner anvil 108 above the blind rivet 63, with the rivet head 119 normally drawn up against outer anvil 102, while the upwardly projecting collar 121, preferably integral with the head projects up into the outer anvil against the inner anvil.

Referring again to the channel-shaped lower arm 68 which at the rear end 73 is slidably supported on stationary block 16, it may be noted that the front end 74 is slidably supported on a stationary bearing member 122 (Figs. 15, 16 and 17) fixed within the spindle casing and resting on interior casing shoulder 123 and prevented from turning or being displaced by a plug or screw 124 extending into the same through the front wall of the spindle casing, said bearing member being provided with a seat 125 forming the actual front support of the lower arm 68. Beneath the forward end 74 of the latter, but rearwardly of seat 125 is a flange or reinforced portion 126 forming the upper end of the inner anvil thrust bushing 115 which is disposed in appropriate position to receive the end of the mentioned lower arm whenever the same is withdrawn from stationary seat 125 by a rearward movement of said arm. The means for thus shifting the arm in proper order with preceding pulling of the mandrel and setting of the rivet will now be considered.

Upon one of the bushings 81 which form the pivoting center for the upper arm 75 is mounted a shifting lever 127, having a downwardly projecting lug or finger 128 extending into a slot or recess 129 in the rear portion of the lower shiftable arm 68, so that when the lever is swung counterclockwise, the finger 128 will shift lower arm 68 correspondingly rearward. The upper end of lever 127 is pivotally connected by a pin 110 to a clevis or connecting link 130 having a nut 131 screwed upon one end of the link and being flanged for engagement with a shift lever return spring 132. The latter is located within spring sleeve 133 fitted into counterbore 134 in the upper part of casing 10 and abutting the adapter 11 so as to prevent displacement of the sleeve. The sleeve is provided with inwardly projecting lug 135 serving as an end stop for spring 132 in order to allow compression of said spring toward said lug by the shift lever with simultaneous longitudinal shifting of lower arm 68, such compression of the spring causing it to tend to return the lever and arm subsequently to initial position. The bore 136 in which previously mentioned valve bushings 54 and 55 are fixed is substantially in line with counterbore 134 so that the front end 137 of slidable shift valve 50 will strike the rear end of link nut 131 when the valve is moved forward. Between the latter valve and the nut is mounted a shift valve spring 138 tending to cushion contact between the valve and nut and begin to exert pressure against the nut when the valve is first caused to move toward the same.

It has already been mentioned that when the trigger 25 is pressed toward the grip member 13 the throttle valve 38 opens, with the result that pressure fluid from inlet port 46 will travel up through passage 47 into upper valve chamber 49 and thence through gap 56 down behind piston 57, driving the latter forward. If then the mandrel is in position in the spindle chuck, with a rivet shell mounted on said mandrel, such forward movement of the piston is of course transmitted through piston rod 61 to wedge 65 which raises upper arms 75 through roller 79, and as ends 85 of said arms engage in the spindle recesses 86, the arms will correspondingly raise spindle 88 and chuck 95, and the mandrel 101 will be drawn upward while the head 119 of rivet 63 is held stationary against anvil 102 until the head 139 of the mandrel is drawn up into definite contact with rivet shell 141. The piston then continues to force the wedge forward and the mandrel will begin to exert sufficient pressure on the shank end of the rivet shell, due to the powerful pull of the upper arm 75, 85 and of the spindle 88 to buckle or bulge the shank as shown at 142 in Figs. 11, 19 and 22. As best seen in Fig. 22, the second mandrel and rivet shell appear in enlarged form in the same stage of operation as in Fig. 11 and in proper relation to a pair of work sheets 143, 144 which are intended to be riveted together. In this Figure 22, it is clearly evident that the mandrel has a locking groove or recess 145 spaced a short distance from the head 139 and immediately above the groove is a rib 146 of equal diameter with the mandrel shank 101 generally, and above the rib again is a breakneck or recess 147 which is designed to be the weakest portion of the mandrel so as to encourage fracture thereof under the proper conditions.

However, when the rivet has been set thus far it begins to offer such formidable resistance to further raising of the spindle and chuck that forward travel of the wedge and consequently of the piston ceases. Assuming that the throttle valve is still maintained open by the trigger so that pressure fluid continues to flow to the rear portion of piston chamber 48 through passage 47, although without further effect on the piston, it is self-evident that the pressure will tend to build up behind said piston to a high level. In the rear of the cylinder casing is a relief valve 148 normally held against valve seat 149 in a fixed valve bushing 151 (Figs. 11, 19 and 23) by spring 152 within pressure adjusting screw 153. This screw by manipulation serves to adjust the pressure at which the spring will allow the valve to open and a set screw 154 is adapted to set a plug 155 against screw 153 to fix the same in any attained or adjusted position. When the pressure in the rear of the piston becomes sufficient to open the valve by overpowering the valve spring, the pressure fluid in the rear piston chamber will pass into relief valve chamber 156 and travel up through passage 157 into the rear shift valve chamber 49 in bushing 54 to the rear of valve head 52 of shift valve 50 and within the closed valve cap 158. The pressure fluid will immediately shift the latter valve from the position of Figs. 5 and 23 a short distance in the forward direction to an intermediate position in which the front end 137 of said valve abuts the rear end of link nut 131 and occupies the position illustrated in Fig. 11, wherein valve head 53 has uncovered main exhaust passage 159 and connects the interior of the rear piston chamber to atmosphere through the latter causing spring 162 to force

piston 57 to its rearward position and permitting spring 152 to seat valve 148 to entrap high pressure air in back of valve 50. A shield 160 is secured by screws 161 (Fig. 23) or other means to the exterior of casing 10 to deflect the issuing spent pressure fluid rearwardly in order to avoid annoyance to the operator.

As wedge 65 starts to recede upon the opening of exhaust port 159, its pressure against arm 10 68 is relieved, since the partially upset rivet and spring 118 hold arms 75 in their elevated position, and air pressure back of valve 50 causes the valve to advance further and shift the forward end of arm 68 off of shelf 125 and on to shelf 126. The shift of arm 68 occurs as follows: as valve 50 advances from the position of Fig. 5 to that of Fig. 11 to that of Fig. 19 it uncovers small ports 163 and closes port 51 which formerly communicated through port 56 with the back of piston 57. Upon the uncovering of ports 163, live air passes from passage 47 through grooves 164 and ports 163 to the back of valve 50 thus continuing the forward motion initiated by the high pressure air originally trapped back of valve 50. As the valve 50 moves farther forward portion 52 enters sleeve 55 thus in effect closing exhaust 159. As valve 50 moves farther forward it opens port 56 and is forced to the extreme forward position shown in Fig. 19.

In the newly attained position, the shift lever 127 by means of the lower end or finger 128 has drawn the lower arm 68 rearward a sufficient distance to remove the front end 74 fully from off the stationary seat 125 and exclusively upon the flange 126 of thrust bushing 115 of the inner anvil. The shift valve by its rear valve head has now also covered the exhaust port 159 and again opened ports 51, allowing pressure fluid to flow in through valve chamber 49, and by way of gap 56 into the rear piston chamber again to drive the piston with its piston rod and associated wedge forward. Due to the shifted position of valve 50 the relief valve will no longer act to limit the operation of the piston as it is exposed to pressure on both sides. Tension will thus again be applied to the mandrel by the renewed raising or pulling movement of spindle 88 and its associated chuck, but in this instance the downward pressure exerted by the wedge through roller bearings 66 is transmitted by the front end 74 of the track member or lower arm 68 solely to the thrust bushing 114 provided below with the anvil thrust washer 109 directly engaging against inner anvil 108, which in turn abuts the upper end of integral collar 121 on the rivet shell. With the entire pressure of the inner anvil exerted upon said collar while the rivet is powerfully held with its head 119 against outer anvil 102, and the pressure now being capable of rising to any desired height because the relief valve is disabled, the pressure upon collar 121 is soon so great (Fig. 19) that it abruptly breaks loose from head 119 and is forced down into the hollow portion 165 in the rivet head and the corresponding locking groove 145 in the mandrel to become firmly fixed therein as shown at 166 in Fig. 22.

When the collar has thus been imbedded in the rivet head, the pressure of the fluid within the piston chamber will continue to rise and the resulting tension on the mandrel will correspondingly increase until said mandrel suddenly snaps or fractures in the breakneck portion 147 immediately above the rivet head and the mandrel rib 146, leaving the lower end 100 of the mandrel

permanently a part of the set rivet. The fracture of the mandrel suddenly releases the piston with its rod and wedge, the pressure fluid behind the piston also tending to precipitate the latter forward, and in order to prevent injury to the same or to portions of the cylinder casing, the piston return spring 162 engages against the plate 167 having a shock absorbing rubber or other resilient ring 168 secured by any suitable means in the cylinder casing. The fracture of the mandrel which immediately frees the tool from the work is at the same time the signal for the operator to release the trigger and shift the apparatus to a new rivet hole with a new mandrel and rivet shell inserted and held by the chuck, the insertion of the new mandrel causing the chuck to release the serrated cast-off stump of the old mandrel and allowing the same to be pushed up through the hollow spindle toward the ejector chute 91. When the new mandrel with its mounted shell is in position, the apparatus is immediately ready for a new cycle of operation automatically carried through by the apparatus itself upon merely pressing the trigger and holding the same until the cycle is completed.

When the trigger is released, the throttle valve is closed by being shifted forward by spring 42 so that neck 45 of the valve is exposed to the throttle exhaust port 169, which allows free escape of pressure fluid from passage 47 through said exhaust port, thus clearing the piston chamber of pressure fluid, and this circumstance permitting the spring 162 to return piston 57 to initial position against rear stop 62 and springs 132 and 138 to return shift valve 50 to extreme rear position. As soon as rear valve head 52 in moving rearward closes ports 51, the residual fluid in rear valve chamber 49 and passage 157 is prevented from being trapped in said chamber in a manner which might prevent full return of the valve, by escaping through the small ports 163 communicating through passages 164 with passage 47 until valve head 53 covers said small ports. Then the remainder of the fluid in the last stage of the return movement of the valve escapes through a rearwardly open longitudinal passage 171 in the valve (Fig. 23) communicating through passage 172 in said valve head, with peripheral groove 173 during said movement registering with main exhaust port 159 and releasing the final residue of pressure fluid to atmosphere which frees the valve so that it may return to make contact with valve cap 158.

While the piston and valves return to initial positions, the wedge is also withdrawn rearwardly to remove all operative pressure from beneath roller 79 and from lower arm or track member 68. In order for the front end of the latter to be capable of resuming its position on seat 125 when the lower arm is shifted forward by clockwise movement of shifting lever 127, a pair of springs 174 are mounted exteriorly of upper arms 75, each being rearwardly looped about a supporting washer 175 (Figs. 8 and 20) secured by a screw or rivet 176 to its respectively adjacent upper arm, with the short leg 177 of each spring confined against a stud or screw 178 upon the same upper arm. A spacing sleeve 179 (Figs. 2 and 7) surrounds the rivet 176 and cooperates with spacer rivets 76 and transverse shaft 71 to maintain the side arms 75 in parallel relation. The relatively longer upper leg of each spring extends forward over the sides of lower arm 68 and at its front end 180 has a link 181

(Figs. 2, 3, 5, 11 and 19) secured thereto by the end 180 extending through link slot 182 and the link seated in recessed portion 183 of the spring. At the bottom the springs are hooked from beneath into apertures 184 in the forwardly directed projections 185 upon said lower arm. The two springs together tend to raise the arm as soon as the strain of the wedge is removed by the wedge being freed from operative contact with roller 79 so that the lower arm will immediately be raised to the level of the mentioned seat 125 for restoration thereto. In order to maintain said lower arm within operative bounds, the forward shoulders 186 thereof form upper limiting edges adapted to engage against the foremost spacer rivet 76, while at the rear the pendent lugs 187 upon upper arms 75 extend down to within a slight distance from the lower arm and prevent the same from jumping off the support block 16. In addition the latter block terminates in a rear stop 188 serving to prevent undue rearward displacement of said lower arm.

Also in connection with the inner anvil thrust bushing, the upper reinforcement or flange 126 is limited in downward movement as a precaution by the rearward projections 189 integral with the stationary bearing member 122 within the spindle casing, so that even if the inner anvil should break, crumble or be missing, the thrust washer 109 will be prevented from striking anvil 102. In order to facilitate operation and allow access to the inner anvil as well as to insert the outer anvil and even have access to the thrust washer, retainer 111 as well as the chuck, the spindle casing has a forward cut away portion 191 (Fig. 1) exposing thrust bushing 114 and portions of the mentioned parts. This cut away portion also gives access to a broken mandrel or part in case the same becomes stuck in the chuck and the latter or any other part requires special attention during operation. On the other hand, the cylinder casing has a rear screw plug 192 which may be removed for inspection and lubrication of the piston, when desired.

From the above description it might seem that one complete cycle of operation would extend over a considerable period of time. The actual time consumed, however, in a commercial embodiment of the invention, from the instant the trigger is pulled, until the rivet head is formed, mandrel locked in place, mandrel broken, trigger released and all parts returned to their normal position, is only about one second.

While the invention has been described with particular reference to the art of setting blind rivets, it should be understood that the invention, or at least certain features thereof, are applicable for other uses such as dimpling, grommet setting, attaching hooks or shelf brackets to sheet metal walls, and establishing pin-to-plate connections generally.

What is claimed is:

1. Apparatus for setting a rivet assembly of the type including a shell and a pin extending through the shell for upsetting the latter at one side of a structure, said apparatus comprising a stationary anvil constituting a stop for the shell holding the latter in position during operation, a movable spindle member having means for gripping the pin, actuating means for moving the spindle member and subjecting the pin to tension, a fixed support, a second movable spindle member having a portion for engaging a portion of the shell to apply pressure thereto, a shiftable member disposed in position for receiving the re-

action of the first spindle member when the latter is operated by said actuating means, said shiftable member having a portion resting on the fixed support when a predetermined tension is applied to the pin to upset the shell against the side of the structure, and means for shifting said portion of the shiftable member off the fixed support and upon the second spindle member and thereby transferring said reaction to the latter for applying a renewed tension to said pin while applying pressure to the shell through the second movable spindle member.

2. Apparatus for applying to a sheet metal structure a rivet assembly of the type including a shell and a pin extending through the shell for upsetting the latter at one side of the structure, said apparatus comprising a stationary anvil for holding the shell in position during operation, a movable spindle member having means for gripping the pin, a movable arm means engaging the spindle member to move the latter and thereby subject the pin to tension, a fixed support in said apparatus, a second movable spindle member having an anvil portion for engaging a portion of the shell to apply pressure thereto, a movable power driven wedge adapted to engage with a portion upon said movable arm in order to move the latter and thereby also the spindle member, a shiftable second arm constantly supporting said movable wedge in all positions of the latter and having one end adapted to rest on the fixed support in order to allow the wedge to actuate the movable arm and operate the first mentioned spindle member and thereby subject the pin to sufficient tension to operate the shell, said shiftable second arm being effective when the mentioned one end thereof rests on the second spindle member to cause the anvil associated with the latter to apply pressure to the shell, automatic means for shifting said second arm from off said fixed support and upon said second spindle when the shell has been upset, and means for controlling the operation of said wedge.

3. Apparatus for setting a blind rivet according to claim 2, in which the arm means includes a pair of corresponding arms disposed at the sides of the shiftable second arm, and in which resilient means are included tending to support said shiftable arm in raised position.

4. Apparatus for setting a blind rivet shell having a hollow shank terminating in a head at one end, with the aid of a mandrel inserted in said rivet shell and provided with a head exteriorly of the shank of the rivet shell, including a casing having a cylinder containing a reciprocable piston, a rigid primary anvil upon the casing for engaging against the head of the rivet shell, operable means having facilities for gripping the shank of the mandrel beyond the head of the rivet shell and movable with respect to the anvil in order to pull upon said mandrel to a predetermined extent while the rivet head is held against the anvil, driving means actuated by said piston during the working movement thereof effective to cause the pulling movement of said operable means to set the rivet shell, further operable means including a secondary anvil capable of engaging independently against a portion upon said rivet shell, a shiftable member cooperating with said driving means, an unyielding support for each end of said shiftable member in said casing, and automatic means effective upon setting of the rivet shell to shift one end of the shiftable member off its support upon a portion of the further operable means while the other end of said

shiftable member remains on its support, whereby the reaction of the pull on the mandrel is taken off the primary anvil and transferred to the secondary anvil.

5. Apparatus for setting a blind rivet according to claim 4 in which the automatic means includes a fluid operated lever connected to the shiftable member to shift the latter and has a valve controlling the flow of pressure fluid for causing operation of said lever when a predetermined high pressure of fluid has been attained in the piston chamber of the cylinder.

6. Apparatus for setting a blind rivet having a hollow shank terminating in a head at one end, with the aid of a mandrel inserted in said rivet and provided with a head exteriorly of the shank of the rivet, including a casing having a cylinder containing a reciprocable piston, an inlet port for admitting pressure fluid into the cylinder to propel the piston in at least the working direction from an initial position, a rigid anvil upon the casing engageable against the head of the rivet, a spindle reciprocably mounted in a portion of said casing having a chuck for gripping the shank of the mandrel beyond the head of the rivet, arm means pivotally mounted in the casing with one end thereof engaging with said spindle and effective to raise the latter, a shiftable arm also disposed within said casing, an unyielding support for each end of said shiftable arm, an independently reciprocable spindle member mounted adjacent to said spindle and having a movable anvil member associated therewith in effective position to engage against a locking member upon the rivet head, roller means mounted upon said first mentioned arm means, a wedge member connected to the piston to be moved thereby while riding on the shiftable arm with the latter serving as a stationary track therefor and while said wedge member engages with said roller means to raise the first mentioned arm means during working movement of said piston and wedge member in order to cause the spindle and chuck to rise and pull upon the mandrel and thereby set the rivet while holding the head of the rivet against the rigid anvil, a shifting lever pivotally mounted in association with said casing and having one end connected to said shiftable arm, a fluid operated piston valve capable of operating said shifting lever in one direction to effect shifting of said shiftable arm to remove one end thereof from its support upon said independently reciprocable spindle member while the other end of said shiftable arm remains on its support, and a relief valve communicating with the piston chamber controlling the flow of pressure fluid from said inlet port to said fluid operated piston valve and allowing pressure fluid to operate the latter upon attainment of a predetermined high pressure in the piston chamber when the rivet has been set.

7. Apparatus for setting a blind rivet according to claim 6, in which resilient means are included tending to raise the spindle and further resilient means are associated with the shifting lever and the fluid operated piston valve to return the latter to initial position.

8. Apparatus for setting a blind rivet according to claim 6, in which resilient means are associated with the shifting lever and the fluid operated piston valve to return the latter to initial position, and wherein the shifting lever has a portion associated therewith spaced a distance from the fluid actuated piston valve in initial position.

sition of the latter to provide a lost motion interval between the initial movement of said piston valve and commencement of the movement of the shifting lever caused by said piston valve.

9. A power operated tool for upsetting a fastener or rivet of the type which consists of a pin surrounded by a shell; said tool comprising a primary anvil and a secondary anvil, said anvils being disposed coaxially with each other and arranged to engage different portions of the shell of the rivet, a cylinder providing a piston chamber, a fluid pressure operated piston reciprocable in the cylinder, a pair of complementary pulling and pushing elements, the pulling element having a chuck adapted to grip the pin and the pushing element being adapted to abut against the primary anvil and the secondary anvil in succession, and power transmitting means operated by the piston for imparting relative motion between said complementary pulling and pushing elements at a pressure substantially in excess of the force acting on the piston.

10. A power operated tool for upsetting a blind rivet of the pin and shell type comprising a chuck adapted to grip and pull the pin, a primary anvil and a secondary anvil arranged successively to abut against different portions of the rivet shell to apply the reactive force thereto as the pin is being pulled, a power driven piston having an extension operatively connected to the chuck to impart a pulling motion thereto, a track over which the piston extension rolls, said track being arranged to receive the reaction of the piston extension, said track having a portion resting on the primary anvil and being shiftable to cause said portion to rest on the secondary anvil.

11. A power operated tool according to claim 10 which comprises means for automatically shifting the track upon the development of a predetermined pressure in back of the piston.

12. A power operated tool for upsetting a blind rivet or similar structure of the type consisting of a pin and a surrounding shell; said tool comprising a chuck adapted to grip and pull the pin, a primary anvil and a secondary anvil arranged successively to abut against different portions of the shell to apply the reactive force thereto as the pin is being pulled, a lever operatively connected to the chuck to pull the latter, a roller carried by the lever, a power driven wedge for actuating the roller, a track on which the wedge is mounted for reciprocating motion, said track being arranged to seat selectively on the primary anvil and the secondary anvil to transmit the reactive force of the wedge against the shell as the pin is being pulled.

13. A portable power operated tool comprising a cylinder forming a piston chamber, a fluid pressure operated piston reciprocable therein, a forward extension on said cylinder forming a handle grip member, a spindle casing secured to the front end of the grip member and extending downwardly therefrom, an anvil secured to the lower end of the spindle casing and adapted to abut against a work piece and being perforated to permit the passage of a mandrel therethrough, a pulling spindle mounted for reciprocation in the spindle casing, a chuck carried by the pulling spindle and having jaws arranged for gripping and pulling the mandrel, a track mounted in the cylinder extension and having an end supported on the spindle casing, a piston extension supported on the track for forward and rearward rolling motion, and a lever connected to the pull-

ing spindle to operate the same, said lever having a roller interposed in the path of the piston extension, the associated surface on the piston extension being inclined to form a wedge, whereby forward movement of the piston is effective to pull the spindle and chuck upwardly while applying the reactive force to the track and anvil, and means responsive to the development of a predetermined pressure in back of the piston to shift the supported end of the track off the spindle casing, thereby relieving said anvil of pressure.

14. Apparatus for applying pressure successively to two portions of a workpiece with the aid of a mandrel inserted through said workpiece and provided with a head exteriorly of the workpiece, including a casing having a cylinder containing a reciprocable piston, a rigid primary anvil upon the casing for engaging against one portion of the workpiece, operable means having facilities for gripping the shank of the mandrel and movable with respect to the anvil in order to pull upon said mandrel to a predetermined extent while the workpiece is held against the anvil, driving means actuated by said piston during the working movement thereof effective to cause the pulling movement of said operable means to deform the workpiece, further operable means including a secondary anvil capable of engaging independently against a second portion of said workpiece, a shiftable member cooperating with said driving means, an unyielding support for each end of said shiftable member in said casing, and automatic means to shift one end of the shiftable member off its support upon a portion of the further operable means while the other end of said shiftable member remains on its support, whereby the reaction of the pull on the mandrel is taken off the primary anvil and transferred to the secondary anvil.

15. Apparatus for deforming a workpiece with the aid of a mandrel inserted through said workpiece and provided with a head exteriorly of the workpiece, including a casing having a cylinder containing a reciprocable piston, an inlet port for admitting pressure fluid into the cylinder to propel the piston in at least the working direction from an initial position, a rigid anvil upon the casing engageable against a portion of the workpiece, a spindle reciprocably mounted in a portion of said casing having a chuck for gripping the shank of the mandrel, arm means pivotally mounted in the casing with one end thereof engaging with said spindle and effective to raise the latter, a shiftable arm also disposed within said casing, an unyielding support for each end of said shiftable arm, an independently reciprocable spindle member mounted adjacent to said spindle and having a movable anvil member associated therewith in effective position to engage against a second portion of the workpiece, roller means mounted upon said first mentioned arm means, a wedge member connected to the piston to be moved thereby while riding on the shiftable arm with the latter serving as a stationary track therefor and while said wedge member engages with said roller means to raise the first mentioned arm means during working movement of said piston and wedge member in order to cause the spindle and chuck to rise and pull upon the mandrel and thereby deform the workpiece while holding the head of the latter against the rigid anvil, a shifting lever pivotally mounted in association with said casing and having one end connected to said shiftable arm, a fluid operated

piston valve capable of operating said shifting lever in one direction to effect shifting of said shiftable arm to remove one end thereof from its support upon said independently reciprocable spindle member while the other end of said shiftable arm remains on its support, and a relief valve communicating with the piston chamber

controlling the flow of pressure fluid from said inlet port to said fluid operated piston valve and allowing pressure fluid to operate the latter upon attainment of a predetermined high pressure in the piston chamber when the workpiece has been deformed.

HOWARD R. FISCHER.
